Wm. F. George

UNITED STATES PATENT OFFICE.

WM. F. GEORGE, OF CINCINNATI, OHIO.

STOVE.

Specification of Letters Patent No. 29,687, dated August 21, 1860.

To all whom it may concern:

Be it known that I, WILLIAM F. GEORGE, of Cincinnati, in the county of Hamilton and State of Ohio, have invented a new and useful Improvement in Summer-Stoves; and I do hereby declare that the following is a full and exact description thereof, reference being had to the accompanying drawings, and letters of reference marked thereon, 10 making a part of this specification.

My invention relates more especially to that class of cooking or baking stoves in which the heat is produced by burning gas or alcohol; or by the application of a brazier 15 of burning wood coals, which as they consume without evolving any smoke, do not necessitate the use of smoke pipes.

The stoves constructed on my improved plan, are particularly applicable to summer 20 cooking, the principal object attained by my improvement being the proper cooking or baking of the eatables with but a very small consumption of combustible materials, so that the temperature of the room containing the stove will scarcely be thereby affected, and consequently in warm weather, the whole of the cooking or baking may be effected, without having any oppressive and disagreeable heat created in the place; and 25 the nature of my invention consists in certain novel and peculiar formation, and arrangement of parts constituting the whole stove, an accurate description of which I will now proceed to give in detail.

30 In the accompanying drawings Figure 1 is a perspective view of the stove. Fig. 2 is a central sectional elevation thereof.

Like letters of reference indicate corresponding parts in the two drawings.

40 A is the outer casing of the stove made in the form shown—that is circular and enlarging gradually from the base B toward the top for about two thirds of the whole height and thence contracting toward the center by two different planes of convergence the last of which terminates in the base of a ring C which is capped by a perforated plate D which has a central aperture receiving a vessel E. The base B may 45 be of any convenient form to support the stove above a flame of gas or an alcohol lamp, or a pan of burning coals, or its place may be supplied by a coke or charcoal burning furnace to support the stove and 50 contain the appropriate fuel.

55 F is the door of the oven. It may be a

double door as represented or it may be in one part.

The casing A is double, consisting of an outer and an inner case of precisely similar form, affording a thin annular space *i* surrounding the entire body of the stove (except the part occupied by the door). The outer and inner case are united at the base and at the point of contact with the ring 60 C by the insertion of annular plates or rings *b b*. This thin chamber may be left as a confined air chamber or it may be filled with any convenient familiar nonconducting substance such as plaster of paris or 65 hydraulic cement.

H is the oven. It has a form corresponding somewhat with the form of the outer case A, and is supported within the case A by horizontal supports *a a* secured to the 70 inner or concave face of the latter reaching across the narrow space and attaching to the outer or convex face of the oven. The diameter of the oven at its lower end, upon a plane with the base of A, is proportionally 75 smaller than A, affording an annular space between the two, of considerable thickness, but this space is gradually diminished in thickness toward the upper end of the apparatus until at the point where the outer 80 case A unites with C the space J is reduced to an area barely sufficient to permit of the upward passage and escape of the gases arising from combustion; from this point the oven converges upwardly to an apex within 85 the ring C. The lower end of the oven H is composed of soap stone, fire clay or a thick plate of cast iron as K capable of resisting the action of the flame or intense heat of 90 coals with which it will be in close proximity.

95 G is a casing surrounding the space from the door F into the oven.

I is a perforated diaphragm upon a plane or level with the lower line of the door, 100 serving to support vessels containing the food in the process of cooking. Another one or more diaphragms may be introduced into the oven if desired. These should be perforated as shown or made of wire for the 105 purpose of diffusing the heat which rises in a direct line from the lower point of the oven and which would otherwise heat and cook unevenly.

110 The vessel E which surmounts the stove is conveniently placed where a portion of caloric which would otherwise escape is

utilized for the purpose of heating water or boiling.

The value of a summer stove may be said to depend upon its capacity to preserve and properly apply the heat of combustion to culinary purposes. In a stove constructed upon the plan as herein described ample provision is made for preserving the heat by inclosing the oven within a nonconducting casing, and the form of the oven together with the gradually contracting or diminishing area between the oven and the outer casing is such as to produce the greatest attainable results from a given amount of heat or combustion, practically considered. By this peculiar formation and arrangement of the oven and stove casing, I have fully overcome an important practical difficulty, viz: of distributing the heat from a single point, such as the flame of a lamp or a narrow pan of coals, equally around an inclosure like an oven when the latter is large enough to be useful for domestic purposes.

In my stove a narrow point at the bottom of the oven comparatively remote from the substance which may be cooking in the inside is exposed to the direct and intense action of the heat so as to absorb a considerable portion of it and impart it diffusely into the space within the oven, but the heat not thus absorbed and which passes upwardly through the gradually contracting annular flue *J* is, comparatively speaking, condensed or concentrated as it ascends, so that the upper part of the oven though remote from the source of heat is still under its influence in a peculiar manner and thus becomes sufficiently heated for all the purposes of properly and evenly cooking the substance which may be contained within. It should moreover be remarked that the

general direction of the surfaces which bound the annular flue, being oblique instead of vertical, their action with reference to the heat rays is reverberatory, and this is particularly manifest and effective at that point in the surfaces where the lines begin to converge toward the center at the upper part of the stove, where the ascending heat is reflected from the inner face of the outer casing downwardly and inwardly against the top of the oven.

The lower point of the oven receiving the direct influence of the flame becomes heated to a degree which prevents the condensation of the gases of combustion and the formation of carbon or soot upon the surface.

The body of the stove is not secured to the base, and it is proposed to leave it free to be applied to any convenient furnace, burning coal when so required.

The apparatus is constructed mainly of sheet metal, and of dimensions adapted to the requirements of purchasers.

Having thus fully described my invention what I claim as new and desire to secure by Letters Patent, is—

1. In combination with the outer casing *A*, the oven *H*, of the herein described peculiar shape and form: the same being made to present a gradually increasing sectional area, in the manner as and for the purpose set forth.

2. Gradually diminishing the area of the annular flue *J*, between the outer casing *A*, and the oven *H*, in proportion as the sectional area of the latter is made to increase, in the manner as and for the purpose set forth.

WM. F. GEORGE.
